MARTIN BINDER, OF NEW HYDE PARK, NEW YORK

EXTENSION TABLE

Application filed September 27, 1928. Serial No. 308,671.

The invention relates to furniture construction, more especially to a table having side leaves which are normally concealed underneath the top of the table but may be caused to rise to occupy a plane flush therewith and, when not required, may be readily and conveniently returned to their normal position.

The invention has for its object to simplify the construction and arrangement of the guiding and the controlling mechanism for effecting elevation of a pair of extension leaves simultaneously to the plane of a fixed table top and their return to position beneath the same.

In carrying out the invention, provision is made for guiding a pair of slide members, carrying leaves respectively along opposite sides of a stationary table top, in manner such as to cause the same to be elevated as they are withdrawn from beneath said top, together with control means for preventing return of the slide members over the same path as they are then pushed inwardly to bring the leaves in contact with the corresponding side edges of the table. These control means embody, also, an arrangement for permitting the slides to be returned over their normal guideways when again drawn outwardly and then moved inwardly, thus restoring the leaves carried thereby to the normal position beneath the table top.

In a co-pending application, Serial Number 289,128, filed June 29, 1928, I have disclosed a somewhat similar arrangement for positioning the slide members of suitably mounted, vertically movable slide blocks; but in the present instance, the control mechanism for setting the means barring return of said movable slide blocks is provided at one side of the table only, the said means being common to both of said slide blocks and provided and actuated by said control mechanism to interpose corresponding members when the respective slide blocks are elevated.

I have found that this feature is of decided advantage in positioning the leaves in that play or lost motion in the different slide blocks and mountings will not cause nonsynchronous action and jamming of parts of the

control mechanism, as only one such mechanism is provided.

The nature of the invention, however, will best be understood when described in connection with the accompanying drawings, in which:

Fig. 1 is a plan view of the improved table with portions of the top and extension leaves broken away.

Fig. 2 is a transverse vertical section taken on the line 2—2, of Fig. 1 of the drawings, and looking in the direction of the arrows.

Fig. 3 is a fragmentary section, and illustrates one of the leaves extended or raised to lie flush with the table top.

Fig. 4 is a fragmentary vertical section taken on the line 4—4, Fig. 1 of the drawings, and looking in the direction of the arrows.

Fig. 5 is a plan view of the support for the elevating rollers and slide blocks, as well as of the movable slide-bar for barring return of the said slide blocks.

Fig. 6 is a fragmentary front elevation thereof.

Figs. 7 to 11 are fragmentary plan views illustrating the different positions assumed by the controlling mechanism and cooperating slide bar in the extension of the table leaves to position flush with the table top and their return to a position beneath the said top.

Fig. 12 is a view in perspective of a cam member adapted for engagement with the controlling mechanism.

Referring to the drawings, 20 designates a rigid table member embodying the supporting legs 21 and fixed or stationary top 22, which latter is rigidly secured to the fixed support 20 through suitable brackets or supports 23 attached to the table member 20. The latter is designed to support transversely disposed slide blocks 25 and 26 which are located some distance inwardly from the respective ends of the table and beneath the top 22 thereof. These blocks embody a pair of oppositely extending slide members 27 and 28, each bearing a rack 29 cooperating in turn with a centrally disposed rotatable gear 30, so that as one of the slides is drawn outward-

ly the other will be correspondingly extended but in opposite direction. Extension slides of this type are well-known; and are designed to support corresponding extension leaves 35 and 36 located upon opposite sides of the table top and normally positioned and concealed beneath the same, as indicated in Figs. 1 and 2 of the drawings.

In accordance with the invention, the said 10 slide members of each block are provided with respective cam grooves 37 and 38 which, in turn, are designed to engage rollers 39 and 40 respectively carried by uprights 41 and 42 located upon opposite sides of a slide block 15 and at the opposite ends thereof. As these rollers ride in their corresponding grooves, they are adapted to elevate the corresponding slide members, carrying the blocks sufficiently to guide the leaves supported thereby to 20 a position flush with the table top 22 or to depress said leaves to a position beneath the same when operated to return the said leaves. To effect this positioning of the leaf members to the table, the same are to be manipulated 25 manually, as in first drawing outwardly from the table the said leaves and then pushing them inwardly until contact is made with the top; and in returning the same to their position beneath said top, the action is the reverse.

It will be understood, however, that provision must be made in thus elevating the slide blocks to prevent the same from dropping back to the lowered position during the 30 inward movement; and to this end each block is provided, in addition to perforations for guiding pins 45, with a pair of dowels 46 which extend downwardly from the bottom of a said block and normally into openings 47 provided therefor in the support 20. When the said blocks are then elevated, the dowels are raised sufficiently to clear the corresponding openings 47, into which they normally fit, to permit a bar member 48 to be 40 interposed and temporarily prevent the return of the dowels and attached blocks. This bar 48 is arranged to be longitudinally slideable with respect to the table top or support 20 as by mounting the same on the latter 45 through screws 49 fitting corresponding longitudinal slots 50 of said bar member. The latter, furthermore, has end lateral extensions 51 adapted, when the said bar is longitudinally adjusted, in manner hereinafter set forth, to be positioned over the corresponding dowel openings 47 and thus effect a bar to the return of the slide blocks so that the leaves will be caused to remain in the plane 55 of the table top when they are pushed inwardly, as aforesaid.

The sliding motion of the bar member 48 for this purpose is effected from the motion of one of the slides which to this end has secured to its inner side a bracket 55 carrying 60 a lever 56; and on one end of this lever is

mounted a roller 57. The latter is adapted, in turn, to engage with a fixed cam member 58, secured to the support 20, to deflect the opposite and pointed end of said lever outwardly or away from the slide so that it 70 may be located behind a pin 59 fixed to and extending upwardly from the control bar 48.

The relative positions of lever 56, pin 59 and cam 58 are shown in Fig. 7 of the drawings, for the normal position of the table 75 leaves 35 and 36 beneath the table top 22.

As a slide is then drawn outwardly, lever 56 moves in a direction toward the pin 59, eventually getting behind the same. Thereupon, with further movement in the same direction (indicated by the arrow, Fig. 8) lever 56 will engage the pin and cause the same to be pushed over to the position indicated by the dotted lines, Fig. 8, and move the bar 48 accordingly. In then pushing inwardly 85 the slides, which have been raised in the meantime, and in order to bring the leaves flush with the table top, bracket 55 will move in the direction of the arrow, Fig. 9, and cause the roller 57 to engage with a cam 60, 90 extending from cam 58 at a higher level, to swing the point of lever 56 to a position substantially against its slide so as to locate it in front of the pin 59 in its innermost position, Fig. 10. The said lever will then contact with the pin 59 as the slides with leaves are again drawn outwardly in the final operation of returning the latter beneath the table top; and the said pin will thus be returned to its original position (indicated by the 100 dotted line position, Fig. 10) being forced thereto by the movement of said lever in the direction of the arrow, Fig. 10. The dowels 46, therefore, are free to return through their openings when registered therewith and the slide blocks will correspondingly drop; and with inward movement of the leaves, the same will be positioned beneath the table top, being guided by the cam grooves in their supporting slide members.

In returning the said leaves to their final position beneath the table top, the slide with leaves pushing the latter inwardly from their extreme outward position will move thereby the bracket 55 with lever 56 in the direction of the arrow, Fig. 11, and at the lower level where the roller 57 eventually engages cam 58 to swing the lever away from the slide surface and restore it to the position indicated in Fig. 7 for repetition of the cycle when the leaves are again to be located flush with the table top and then restored to position beneath the same.

I claim:

1. An extension table, comprising a fixed 125 top, a pair of vertically movable slide blocks positioned beneath the same and each carrying a pair of coacting slide members horizontally movable relatively thereto in opposite directions, table leaves carried by the 130

respective slide members and positioned thereby normally beneath the said table top, means to guide said slide members with leaves to the plane of the table top and to elevate thereby their slide blocks, and means common to both slide blocks, movable relatively to the table and actuated by the movement of a slide member of one of said blocks to bar the return of both of the elevated blocks to normal position.

2. An extension table, comprising a fixed top, a pair of vertically movable slide blocks positioned beneath the same and each carrying a pair of coacting slide members horizontally movable relatively thereto in opposite directions, table leaves carried by the respective slide members and positioned thereby normally beneath the said table top, means to guide said slide members with leaves to the plane of the table top and to elevate thereby their slide blocks, and means common to both slide blocks, movable longitudinally of the table and actuated by the movement of a slide member of one of said blocks to bar the return of both of the elevated blocks to normal position.

3. An extension table, comprising a fixed top, a pair of vertically movable slide blocks positioned beneath the same and each carrying a pair of coacting slide members horizontally movable relatively thereto in opposite directions, table leaves carried by the respective slide members and positioned thereby normally beneath the said table top, dowel pins carried by the slide blocks and normally fitting suitable openings of the table, means to guide said slide members with leaves to the plane of the table top and to elevate thereby their slide blocks, and means common to both slide blocks, movable relatively to the table and actuated by the movement of a slide member of one of said blocks to cover the said openings.

4. An extension table, comprising a fixed top, a pair of vertically movable slide blocks positioned beneath the same and each carrying a pair of coacting slide members horizontally movable relatively thereto in opposite directions, table leaves carried by the respective slide members and positioned thereby normally beneath the said table top, dowel pins carried by the slide blocks and normally fitting suitable openings of the table, a bar member extending longitudinally of the table having end lateral extensions adapted to cover said openings, and means actuated from a slide member of one of said blocks to longitudinally move said bar.

5. An extension table, comprising a fixed top, a pair of vertically movable slide blocks positioned beneath the same and each carrying a pair of coacting slide members horizontally movable relatively thereto in opposite directions, table leaves carried by the respective slide members and positioned

thereby normally beneath the said table top, dowel pins carried by the slide blocks and normally fitting suitable openings of the table, a bar member extending longitudinally of the table having end lateral extensions adapted to cover said openings, an upwardly extending pin carried by the said bar member, a lever carried by a slide member of one of said blocks, and a cam fixed to the table, provided with a surface adapted to engage one end of said lever as the said slide member is moved to position the opposite end of the lever behind the pin extending from said bar member and to shift the latter as movement of the slide member is continued.

6. An extension table, comprising a fixed top, a pair of vertically movable slide blocks positioned beneath the same and each carrying a pair of coacting slide members horizontally movable relatively thereto in opposite directions, table leaves carried by the respective slide members and positioned thereby normally beneath the said table top, dowel pins carried by the slide blocks and normally fitting suitable openings of the table, a bar member extending longitudinally of the table having end lateral extensions adapted to cover said openings, an upwardly extending pin carried by the said bar member, a lever carried by a slide member of one of said blocks, and a cam fixed to the table, provided with a surface adapted to engage one end of said lever as the said slide member is moved to position the opposite end of the lever behind the pin extending from said bar member and to shift the latter as movement of the slide member is continued, said cam being provided with a further surface adapted to engage the lever upon outward return movement of the slide member to locate the said opposite end in a position ahead of the said pin for engagement therewith to return the bar member to normal position as the slide member is moved in the reverse direction.

In testimony whereof I affix my signature.
MARTIN BINDER.
